UNITED STATES PATENT OFFICE.

WILLIAM HENRY ALEXANDER, OF LONG BRANCH, NEW JERSEY.

CONCRETE-MOLD.

No. 922,997.

Specification of Letters Patent.

Patented May 25, 1909.

Application filed July 17, 1908. Serial No. 444,112.

To all whom it may concern:

Be it known that I, WILLIAM H. ALEXANDER, a citizen of the United States, and a resident of Long Branch, in the county of 5 Monmouth and State of New Jersey, have invented a new and Improved Concrete-Mold, of which the following is a full, clear, and exact description.

My invention relates to concrete molds, 10 and it has for its object to provide a mold which will more readily permit of a concrete block being formed with its exterior surface of a different mixture from its body; and my invention also has in view to provide means 15 to remove the concrete block from the mold with little trouble, and with no danger of breakage.

Still other objects of the invention will be found in the following complete description 20 of the invention.

In this specification I will describe the preferred form of my invention, but it will be understood that I do not limit myself thereto, as I consider myself entitled to all 25 forms and embodiments of the invention which may be held to fall within the scope of the appended claims.

Reference is to be had to the accompanying drawings, forming a part of this specification, in which similar characters of reference indicate corresponding parts in all the figures, in which—

Figure 1 is a rear elevation of the invention; Fig. 2 is a plan view of the same; Fig. 3 is a perspective view showing a concrete curb block which has been formed in my mold; Fig. 4 is a side elevation of the invention on a smaller scale; Fig. 5 is a sectional side elevation of the invention on the same scale as 40 Fig. 4, but without the removable side and end pieces and the clamps by which they are secured. The body of the mold is also shown in the position which it will assume when the concrete block is deposited; Fig. 6 is a perspective view of the removable end piece; Fig. 7 is a perspective view of the removable side piece; and Fig. 8 is a perspective view of one of the side clamps.

By referring to the drawings, it will be 50 seen that a frame 1, suitably braced, is supported on a platform 2, the platform being mounted on rollers 3. In the frame 1 there are bearings 4, in which is journaled a shaft 5, and to this shaft 5 is secured a body 6, 55 which has an end 7 integral therewith, and which has beneath its bottom, longitudi-

nal strengthening ribs 8, and a transverse strengthening rib 9.

As shown in Fig. 5 of the drawings, the integral end 7 of the body 6 extends below the 60 bottom of the body and unites with the longitudinal supporting ribs 8.

In the construction which I prefer, the bottom of the body 6 and the longitudinal ribs 8 approach each other toward the open end of the body, and at the sides of this open end the nearest longitudinal ribs are continued to the outer surfaces of the bottom of the body as at 10, thus affording the necessary strength to permit members 11 of supports 65 70 12 to engage them, to hold the body of the mold with its bottom substantially in a horizontal plane. These supports 12 are pivoted to the platform 2, so that they may be turned to permit the body 6 to assume the 75 position shown in Fig. 5 of the drawings, thereby permitting the concrete block to be deposited between the members of the platform 2. The members of the platform 2, are connected by a bar 13 which serves to act as 80 a stop for the body when it is rotated in the frame 1, and its bottom assumes the upright position shown in Fig. 5, which will permit the concrete block to be deposited between the members of the platform 2 upon the floor 85 which is but a couple of inches below the lowermost position of the body when it is rotated to the position shown in Fig. 5.

The body 6 is secured to the shaft 5 by 90 means of bolts 14, or by any other appropriate means. It will be understood, however, that these bolts engage the body at opposite sides, so that they will not interfere with the even inner surfaces of the body. Side pieces 15 are provided, one for either side of the 95 body 6, the side pieces being of such a configuration that they will fit snugly against the bottom and the integral end of the body and when these side pieces 15 are in position, an end piece 16 is disposed against the open 100 end of the body, the end piece having tenons 17, one at either side, and tenons 18 at its bottom, the tenons 18 engaging the bottom of the body and the inner sides of the tenons 17 engaging with the side members 15. Side 105 clamps 19 are then placed in position, one at either side of the body, flanges 20 at the ends of the clamps fitting against the outer sides of the tenons 17 and threaded portions 21 of the clamps 19 fitting in slots 22 at the back 110 of the body, as is best shown in Fig. 1. Lever nuts 23 mesh with the threaded portions

21 of the clamps 19, and when these lever nuts are screwed down it will be understood that the flanges 20 will be drawn snugly against the tenons 17 of the end piece 16, which will securely hold the end piece in position; the other sides of the said tenons 17 resting against the side pieces 15 and the tenons 18 of the end piece 16 resting against the bottom of the body 6.

10 When the removable sides and the removable end piece have been adjusted as has just been described, by a movement of a lever 24, the shaft 5 may be rocked, which will bring the bottom of the body 6 to a position substantially horizontal, when the supports 12 may be rotated on their bases so that the members will engage the portions 10 of the body to so support it. The body of the mold may then be filled to the desired depth with the concrete, and by first covering the bottom and the integral end of the body, an outer and finer surface for the concrete block may be obtained. In Fig. 3, this outer and finer surface is shown at 25, while the inner and body of the block is shown at 26.

15 In practice, I find it desirable to make grooves 27 along the sides of the curbing, so that when the several blocks of curbing are in alinement and close together, these grooves 20 27 may be filled with cement to assist in holding the blocks in position. These grooves 27 are formed by providing the side pieces 15 with inner ribs 28.

20 When the body of the mold has been filled 35 with concrete, either with or without an outer dressing along the inner surfaces of the integral end and the bottom of the body, an upper clamp 29, having a flange 31, is used, this flange 31 fitting in a mortise 30 in the 40 end piece 16, and the clamp 29 having an opposite flange 32 which extends over an outer flange 33 at the top of the integral end 7 of the body. This flange 32 has a threaded orifice therein in which meshes the screw of a thumbscrew 34 and when the thumbscrew 34 is turned home, the clamp 29 is held with its flange 31 pressing against the removable end piece 16. The object in using this upper clamp 29 is to furnish additional support for 45 the end piece 16 when the supports 12 are rotated and the shaft 5 is rocked, permitting the body 6 to assume the position shown in Fig. 5; and when the body with the concrete block therein is in the said position, the upper clamp 29 is first freed by means of its 50 thumbscrew 34, which will permit the concrete block to commence to settle with the end piece 16 on the ground, after which the side clamps 19 are freed by unscrewing the 55 screw levers 23, which will finally permit the end piece 16 to rest on the ground, with the concrete block disposed thereon. The upper clamp 29 and the side clamps 19 may then be wholly removed, inasmuch as the flange 31 60 and the upper clamp 29 engage the mortise 65

30 in the end piece 16 and the flanges 20 of the side clamps 19 engage the tenons 17 of the end piece. After the concrete block with the end piece 16 has reached the ground, the side pieces 15 may be readily removed and 70 the mold with its frame and platform may be rolled away. The concrete block 35 will then be found to be resting on the end piece 16, after which the device may be used again, another and similar end piece serving the 75 same purpose as the end piece 16, the several end pieces serving as resting places for the concrete blocks until they are to be removed.

Having thus described my invention, I claim as new and desire to secure by Letters 80 Patent:

1. In a concrete mold, a frame, a body rotatably mounted in the frame, the body having a bottom, one end of the body being permanently secured relatively thereto, removable side pieces for the body which are disposed thereon at either side and form a continuation of the end and extending to the open end of the body, a removable end piece which is disposed at the open end of the body 90 engaging the bottom and sides of the body with its outer side beyond the terminals of the bottom and sides, means for clamping the removable end piece in position and means to free the said means gradually to 95 permit of the deposit of the removable end piece on the ground when the bottom of the body is vertically disposed.

2. In a concrete mold, a frame, a body having trunnions which are journaled in the 100 frame, the body having a bottom, an end piece of the body being permanently secured relatively thereto, removable side pieces for the body which are disposed on either side of the upper surface of the bottom of the body 105 forming a continuation of the end piece and extending to the open end, a removable end piece which is disposed at the open end of the body engaging its bottom and sides, tenons on the removable end piece which engage the 110 terminals of the sides and bottom of the body but which do not prevent the removable end piece from falling when the body is rotated so that its bottom is substantially 115 perpendicularly disposed, means for holding the removable sides and end pieces in position and means to free the said means gradually to permit of the deposit of the removable end piece on the ground when the bottom of the body is vertically disposed.

3. In a concrete mold, a frame, a body having trunnions which are journaled in the frame, the body having a bottom, an end piece of the body being permanently secured relatively thereto, removable side pieces for 125 the body which are disposed on either side of the upper surface of the bottom of the body forming a continuation of the end piece and extending to the open end, a removable end piece which is disposed at the open end of the 130

body engaging its bottom and sides, tenons on the removable end piece which engage the terminals of the sides and bottom of the body but which do not prevent the removable end piece from falling when the body is rotated so that its bottom is substantially perpendicularly disposed, means for holding the removable sides and end pieces in position, means for holding the body with its bottom substantially in a horizontal position means to free the said means gradually to permit of the deposit of the removable end piece on the ground when the bottom of the body is vertically disposed.

4. In a concrete mold, a frame, a body rotatably mounted in the frame, the body having a bottom and an end piece which is permanently secured relatively thereto, removable side pieces for the body which are disposed on either side of the upper surface of the bottom and form a continuation of the end piece, the side pieces extending to the open end of the body, a removable end piece which is disposed at the open end of the body, the removable end piece having tenons which fit against the side pieces and a bottom tenon which fits against the bottom of the body, side clamps having flanges, the flanges fitting against the rear surfaces of the side tenons which do not extend to the rear face of the removable end piece, the side clamps engaging with the first named end piece to hold the removable end piece in position and means to free the side clamps gradually to permit of the deposit of the removable end piece on the ground when the bottom of the body is vertically disposed.

5. In a concrete mold, a frame, a body rotatably mounted in the frame, the body having a bottom and an end piece which is permanently secured relatively thereto, removable side pieces for the body which are disposed on either side of the upper surface of the bottom and form a continuation of the end piece, the side pieces extending to the open end of the body, a removable end piece which is disposed at the open end of the body, the removable end piece having tenons which fit against the side pieces and a bottom tenon which fits against the bottom of the body, side clamps having flanges, the flanges fitting against the rear surfaces of the side tenons which do not extend to the rear face of the removable end piece, the side clamps engaging with the first named end piece to hold the removable end piece in position, there being a mortise in the upper rear surface of the removable end piece, an upper clamp having a flange which fits the mortise, the upper clamp engaging the first named end piece for holding the removable end piece in position and means to move the said clamps slowly relatively to the first named end piece to permit of the deposit of the removable end piece on the ground when the bottom of the body is vertically disposed.

In testimony whereof I have signed my name to this specification in the presence of two subscribing witnesses.

WILLIAM HENRY ALEXANDER.
